UNITED STATES PATENT OFFICE

STANLEY F. OSSING, OF COLUMBUS, OHIO, ASSIGNOR TO THE JEFFREY MANUFACTURING COMPANY, OF COLUMBUS, OHIO, A CORPORATION OF OHIO

SAFETY DEVICE

Application filed December 8, 1925, Serial No. 74,131. Renewed December 23, 1929.

The present invention relates to certain new and useful improvements in safety devices adapted to protect pulverizing machines from injury by fragments of unpulverizable material which accidentally enter the machine with the material which is to be pulverized.

The especial object of this invention is to provide, in a pulverizing machine of the revolving beater type, means to relieve the abnormal strains caused by the passage through the machine of fragments of unpulverizable material.

The means whereby I attain this object are fully set forth in the following specification, and illustrated in the accompanying drawings of which—

Fig. 1 is a transverse vertical sectional view of a pulverizing machine equipped with the devices of my present invention.

Fig. 2 is a front elevation of the machine illustrated in Fig. 1.

Fig. 3 is a fragmentary sectional view, on an enlarged scale, of the machine illustrated in Figs. 1 and 2, showing the method of operation of the safety devices associated with the front wall of the pulverizing chamber.

Like numerals refer to similar parts in the several figures.

In the drawings the numeral 1 refers to a rotor which is mounted upon a shaft 2 journaled in suitable bearings 3, and adapted to be actuated by rotative power derived from any suitable and convenient source through the instrumentality of a belt engaging the pulley 4. The rotor 1 is provided with radially projecting arms 5 the ends of which generate, when the rotor revolves, a substantially continuous pulverizing surface upon which the material to be pulverized may freely float. The journal bearings 3 are preferably formed integral with or are attached to the casing 6 which encloses the rotor, and this casing is adapted to be supported upon any convenient and suitable foundation. The upper part of the casing 6 comprises a pulverizing chamber 7 which is defined by the end walls 8, the back wall 9 and the front wall 10. The back wall 9 is preferably, though not necessarily, inclined to form a hopper like chute down which the material which is to be pulverized may slide into contact with the pulverizing surface. A cover plate 11 may, if desired, be provided to intercept flying fragments of material projected from the rapidly revolving pulverizing surface. The back wall 9 and the end walls 8 are rigidly secured together by suitable fastenings at the corners of the casing, and the forward edges of the end walls 8 are secured in spaced relation by a cross bolt 12 positioned at the upper forward corner of the pulverizing chamber. Suspended from the cross bolt 12 is the front wall 10 of the pulverizing chamber, and this wall is protected from abrasion by the flying fragments of material propelled from the pulverizing surface, by the lining plate 13 at the lower end of which is formed a shelf like projection 14 which extends into close proximity with the pulverizing surface to intercept the advancing fragments of unpulverized material and return them rearwardly of the pulverizing chamber. At its lower end the front wall 10 is held in adjusted relation with the pulverizing surface by the adjusting screws 15 which are screw threaded into suitable nuts 16 attached to the casing. Each of the adjusting screws 15 is provided with two spaced apart collars 17 and 18 which engage the lower end of a lever 19 which is pivotally attached to the front wall 10 by a hinge bolt 20. The lever 19 extends upwardly beyond its pivotal attachment, and near its upper end is pierced by a transverse aperture through which projects a relatively fragile pin 21 the projecting ends of which extend into suitable apertures in the brackets 22 attached to the front wall 10. When these parts are in position, as above described, the front wall 10 and projecting shelf 14 are securely held in operative relation with the pulverizing surface, the strength of the pin 21 being sufficient to resist the strains of normal pulverizing service. When, however, an irreducible body, such as the steel hammer head 23, is accidentally admitted to the pulverizing chamber, and is interposed between the ends of the arms 5 and the shelf 14, as shown in Fig. 3, the pins 21, due to the fragile char-

to form a hopper like chute down which the material which is to be pulverized may slide into contact with the pulverizing surface. A cover plate 11 may, if desired, be provided to intercept flying fragments of material projected from the rapidly revolving pulverizing surface. The back wall 9 and the end walls 8 are rigidly secured together by suitable fastenings at the corners of the casing, and the forward edges of the end walls 8 are secured in spaced relation by a cross bolt 12 positioned at the upper forward corner of the pulverizing chamber. Suspended from the cross bolt 12 is the front wall 10 of the pulverizing chamber, and this wall is protected from abrasion by the flying fragments of material propelled from the pulverizing surface, by the lining plate 13 at the lower end of which is formed a shelf like projection 14 which extends into close proximity with the pulverizing surface to intercept the advancing fragments of unpulverized material and return them rearwardly of the pulverizing chamber. At its lower end the front wall 10 is held in adjusted relation with the pulverizing surface by the adjusting screws 15 which are screw threaded into suitable nuts 16 attached to the casing. Each of the adjusting screws 15 is provided with two spaced apart collars 17 and 18 which engage the lower end of a lever 19 which is pivotally attached to the front wall 10 by a hinge bolt 20. The lever 19 extends upwardly beyond its pivotal attachment, and near its upper end is pierced by a transverse aperture through which projects a relatively fragile pin 21 the projecting ends of which extend into suitable apertures in the brackets 22 attached to the front wall 10. When these parts are in position, as above described, the front wall 10 and projecting shelf 14 are securely held in operative relation with the pulverizing surface, the strength of the pin 21 being sufficient to resist the strains of normal pulverizing service. When, however, an irreducible body, such as the steel hammer head 23, is accidentally admitted to the pulverizing chamber, and is interposed between the ends of the arms 5 and the shelf 14, as shown in Fig. 3, the pins 21, due to the fragile char-

acter of the material of which they are composed, will be fractured by the excessive strain, allowing the lever 19 to rotate about its pivot 20, and thus permit the front wall 10 to swing outwardly upon the pivotal support 12, withdrawing the projection 14 from proximity with the pulverizing surface, and thereby relieving the strain upon the machine and protecting the casing and rotor from destruction. After the hammer head 23, or other irreducible object, is removed from the pulverizing chamber the front wall 10 may be returned to its normal position, a new breakable pin 21 inserted in the lever 19 and brackets 22, and the pulverizing action proceeds as before the interruption.

While I have described my present invention as applied to a pulverizing machine of the well known revolving beater type, it is apparent that these devices are applicable to other types of pulverizing machines, and that the form and arrangement of the parts may be subject to wide variation without departure from the spirit of my invention.

What I claim is:

1. In a pulverizing mill the combination with a casing and a rotor within the casing said casing including a pulverizing chamber, of an abutment at the forward side of said pulverizing chamber adjacent said rotor, a lever pivotally attached to said abutment, a positive member adapted to be fractured by abnormal strains arranged to prevent rotary movement of said lever about its pivotal attachment, and means cooperating with said lever to adjust said abutment relative to said rotor as and for the purpose set forth.

2. In a pulverizing mill the combination with a casing and a rotor within the casing said casing including a pulverizing chamber the forward wall of which is pivotally supported at its upper end and projects downwardly into proximity with said rotor, of a lever pivotally attached to said wall adjacent its lower end, positive means including a member adapted to be fractured by abnormal strains arranged to prevent movement of said lever about its pivotal attachment, and means cooperating with said lever to adjust said wall relative to said rotor as and for the purpose set forth.

3. In a pulverizing mill the combination with a casing and a rotor within the casing said casing including a pulverizing chamber the forward wall of which is pivotally supported at its upper end and projects downwardly into proximity with said rotor, of a lever pivotally attached to said wall adjacent its lower end, a relatively fragile member engaging said lever to prevent rotary movement about its pivotal attachment, and a screw engaging the free end of said lever to adjust said wall relative to said rotor as and for the purpose set forth.

4. In combination, a frame element, a wall element pivoted thereto, means subjecting said wall element to operating impacts, a lever pivoted intermediate its ends to one of said elements, means on the other of said elements engaging one end of said lever, a member securing the other end of said lever in a determined position, said member being frangible under abnormal impact for permitting a swinging of said lever and a consequent yielding of said wall element relative to said frame element.

5. In combination, a frame element, a wall element pivoted thereto, means subjecting said wall element to operating impacts, a lever pivoted to one of said elements, means on the other of said elements engaging said lever, a member blocking said lever in a determined position, said member being frangible under abnormal impact for permitting a swinging of said lever and a consequent yielding of said wall element relative to said frame element.

6. In combination, a frame element, a wall element pivoted thereto, means subjecting said wall element to operating impacts, a lever pivoted to one of said elements, means on the other of said elements for engaging said lever, a member blocking said lever in a determined position, said member being frangible under abnormal impact for permitting a swinging of said lever and a consequent release of the latter from said engaging means, whereby a yielding of said wall element relative to said frame element is allowed.

7. In a machine of the class described, the combination of a casing, a rotor in said casing, said casing including a pivotally mounted wall adjacent the path of said rotor, and latch means positively to hold said wall in predetermined relation to said rotor under normal operating strains and including a frangible element adapted to release said latch means under abnormal strains, said latch means being disposed at the portion of said pivotally mounted wall subjected to the greatest impact stresses.

8. In a machine of the class described, the combination of a casing, a rotor in said casing, said casing including a movably mounted wall adjacent the path of said rotor, relatively movable means connected to said movably mounted wall member, means co-operating with said relatively movable means to hold said wall in a predetermined relation to said rotor, and means positively to hold said wall and relatively movable means in fixed relation under normal operating strains and permit them to move relatively, while maintaining their connected relation, under abnormal strains.

9. In a machine of the class described, the combination of a casing, a rotor in said casing, said casing including a movably mount-

ed wall adjacent the path of said rotor, relatively movable means connected to said movably mounted wall member, means co-operating with said relatively movable means to hold said wall in a predetermined relation to said rotor, and frangible means positively to hold said wall and relatively movable means in fixed relation under normal operating strains and permit them to move relatively, while maintaining their connected relation, under abnormal strains.

10. In a machine of the class described, the combination of a casing, a rotor in said casing, said casing including a pivotally mounted wall adjacent the path of said rotor, latch means positively to hold said wall in predetermined relation to said rotor under normal operating conditions, and means to alter such predetermined relation through said 15 latch means, said latch means including a frangible element adapted to release it under abnormal strains.

In testimony whereof I have hereunto set my hand.
